UNITED STATES PATENT OFFICE.

FLORENCE L. NEWTON, OF PHILADELPHIA, PENNSYLVANIA.

WAIST-LENGTHENER.

SPECIFICATION forming part of Letters Patent No. 678,755, dated July 16, 1901.

Application filed February 20, 1901. Serial No. 48,149. (No model.)

To all whom it may concern:

Be it known that I, FLORENCE L. NEWTON, a citizen of the United States, residing in Philadelphia, Pennsylvania, have invented 5 certain Improvements in Waist-Lengtheners, of which the following is a specification.

My invention relates to certain improvements in women's wearing-apparel, and more particularly to an improved device for maintaining the body of a dress at the waist in a fixed position.

The object of my invention is to provide a simple and inexpensive device by which the downwardly-extending portion of the waist 15 is maintained in position in order to secure what is known as the "long-waist" effect. This object I attain as hereinafter set forth, reference being had to the accompanying drawings, in which—

20 Figure 1 is a view showing my improved waist-lengthener as it is intended to be worn and indicating the preferred method of its attachment to the body of a dress. Fig. 2 is a perspective view of the waist-lengthener, 25 showing it slightly modified to open or unfasten at the back instead of in front. Fig. 3 is a vertical sectional view of a dress-body, showing details of the construction of my waist-lengthener; and Figs. 4, 5, and 6 are vertical 30 sectional views taken on the lines 4 4, 5 5, and 6 6, respectively, Fig. 3.

In the drawings, A is a band or belt, preferably of non-elastic material, to which is sewed a double thickness of any suitable fabric B, as muslin, drilling, &c., approximately 35 V-shaped and having its outline corresponding to that of the lower edge of the dress-body, to which it is to be attached. Within pockets in this part B are stitched pieces of whale-bone, steel, or similar flexible stiffening material, the outlines and the positions of which are indicated at b b in the figures. These 40 pieces are radially placed and serve to keep the part B in a downwardly-extended position. It will be understood that the stiffening material may be secured to the part B in any suitable manner.

The waist-lengthener is preferably made to open in front, as shown in Fig. 1, its parts being held together by hooks and eyes or by 50 any other desired means. The part B may, however, be made in one piece and the band A made to open in the back, as shown in Fig. 2.

In use the lower edge b' b' of the part B of 55 my improved waist-lengthener is sewed or stitched to the inside of the lower edge of the waist or body of a dress, as clearly indicated at c c in Fig. 1, being made to be worn over the skirt and held together as shown. When 60 fastened in place, the stiffening-bones cause the part B to conform to the figure, and the dress-body is evenly and securely held in the downwardly-extending position, thereby obtaining the desired long-waisted effect. 65

It will be understood that the waist-lengthener is not necessarily permanently attached to the dress-body, as it may, if desired, be made detachable therefrom, so that one lengthener may be used with a number of 70 dress-bodies.

I claim as my invention—

1. The combination of a waist having a downwardly-extending, loose front portion, a waistband, a downwardly-extending, stiffened 75 portion attached to said band, the said portion being constructed to conform to the edges of the waist and being attached thereto, substantially as described.

2. The combination of a waist having an 80 open front, with a waistband, the ends thereof being secured together at the front and having two depending sections constructed to be united also at the front, the same being secured to the lower edge of the waist, substantially as described. 85

In testimony whereof I have signed my name to this specification in the presence of two subscribing witness.

FLORENCE L. NEWTON.
